UNITED STATES PATENT OFFICE.

WILLIAM J. GHRAMES, OF ANADARKO, OKLAHOMA.

CUSPIDOR CLEANER AND CARRIER.

1,172,592.

Specification of Letters Patent.

Patented Feb. 22, 1916.

Application filed May 7, 1915. Serial No. 26,615.

To all whom it may concern:

Be it known that I, WILLIAM J. GHRAMES, a citizen of the United States, residing at Anadarko, in the county of Caddo, State of Oklahoma, have invented certain new and useful Improvements in Cuspidor Cleaners and Carriers; and I do hereby declare the following to be a full, clear, and exact description of the invention, such as will enable others skilled in the art to which it appertains to make and use the same.

This invention relates to improvements in cuspidor cleaners.

One object of the invention is to provide a device of this character which is adjustable to various sized cuspidors.

Another object is to provide a device of this character by means of which the cuspidor can be readily handled and cleaned in a sanitary manner and without any great splashing of water therefrom.

Other objects and advantages will be apparent from the following description when taken in connection with the accompanying drawing; in which:

Figure 1 is a front elevation of my improved cuspidor cleaner, Fig. 2 is a top plan view, Fig. 3 is an edge view, and Fig. 4 is a vertical longitudinal sectional view on the line 4—4 of Fig. 3.

Referring particularly to the accompanying drawing, 10 represents a bucket or other suitable receptacle having a portion of one side open, as shown at 11. Secured to diametrically opposite sides of this bucket are the arcuate plates 12, and extending vertically from each of these plates is an upright bar 13. Vertically adjustable on the bars 13 are two sleeves or collars 14, said collars being connected by a cross bar 15, which supports a bearing bracket 16. Rotatably mounted in this bearing bracket is a horizontal shaft 17 having on the outer end a crank handle 18 and on the inner end a bevel pinion 19 which meshes with the pinion 20. Disposed vertically through the bearing bracket, pinion 20, and bar 15, is a shaft 21, the lower end of which is bifurcated as at 22 and provided with the inturned jaws 23. As shown, the outer faces of the furcations are provided with notches 24 and embracing these furcations, is a yoke 26 which at one end is provided with a tooth 25, while at the

opposite end is pivoted a cam lever 27 positioned to bear against the corresponding furcation so that the furcations are moved toward each other when the cam lever is operated in one direction, thus bringing the jaws together upon the brush 37, as herein-after referred to.

Slidable on the shaft 21 is a block 28 which is formed with a pair of laterally directed apertured lugs 29 to which are pivotally connected the inner ends of a pair of plates 30 secured to the backs of the brushes 31. Above the block is a second block 32 which is formed with a laterally directed lug 33 having an inverted T-shaped member 34 secured therein, links 35 being pivotally connected to the T-shaped member and to the other ends of the brush carrying plates.

Both of the blocks are adjustable on the shaft by means of set screws 36. Clamped between the jaws of the furcations of the shaft 21 is a brush 37, this brush being arranged to enter and clean the lower portion of the cuspidor, while the brushes 31 are adapted to be adjusted to various angles by moving the blocks toward and away from each other, for cleaning the face of the flange of the cuspidor.

On the upper end of the shaft 21 is a suitable handle 38 so that the shaft can be raised to permit the positioning of the cuspidor under the device and also for carrying the device from one place to another.

What is claimed is:

A cuspidor cleaner comprising a shaft having a hand-hold at one end and having its opposite end bifurcated and provided with brush clamping jaws, means for exerting clamping action of the jaws, a pair of collars slidably mounted upon the shaft and provided with means for holding them at different points thereon, pairs of toggle links pivoted to and connecting the collars, a brush carried by that link of each pair, nearer the bifurcated end of the shaft, and means for rotating the shaft with respect to the hand-hold.

In testimony whereof, I affix my signature, in the presence of two witnesses.

WILLIAM J. GHRAMES.

Witnesses:

FRANK HEFLEY,
G. M. DAVIDSON.
